LOCK

Frank Ditchfield, Cleveland, Ohio, assignor to The Youngstown Steel Door Company, Cleveland, Ohio, a corporation of Ohio

Application April 16, 1938, Serial No. 202,477

16 Claims. (Cl. 292—285)

This invention relates to locks and more particularly to locks for sliding car doors.

It is an object of this invention to provide locks for sliding doors so designed that they may be mounted in their entirety upon the walls or auxiliary doors of railway freight cars and be adapted for locking engagement with doors slidably related to said walls or auxiliary doors while obviating the attachment of any portion of the locks to said slidably related doors.

A further object is to provide locks for sliding doors in which the stresses imposed thereon shall be distributed over a substantially greater area than is possible with present locks for sliding doors.

A further object is to provide locks for sliding doors capable of distributing stresses imposed thereon over a large area and of absorbing automatically all clearance between the doors and their stops when the locks are in operative position.

A further object is to provide locks for sliding doors mounted for swinging movement in a horizontal plane and capable in locking position of automatically absorbing slack of the doors.

A further object is to provide locks for sliding doors embodying means for automatically taking up slack of the doors and capable of being sealed independently of such means.

A further object is to provide swingably mounted locks for sliding doors embodying tapered pins operable to take up slack of the doors wherein the locks may be swung to inoperative position without raising the pins.

A further object is to provide locks for sliding doors adapted to be fabricated as complete units embodying locking members swingable in a horizontal plane and carrying means cooperable with the locking members to secure automatic take-up of slack of the doors and other means for fastening said members in locking position.

Other objects of the invention will become clear as the description thereof proceeds.

In the drawings forming part of this specification

Figure 1 is a partial elevation showing a lock embodying the instant invention applied to the double doors of an automobile car.

Figure 2 is a vertical section taken on line 2—2 of Figure 1.

Figure 3 is a horizontal section taken on line 3—3 of Figure 1.

Figure 4 is a plan view of a lock base.

Figure 5 is a plan view of a locking member of the lock.

Figure 6 is a view similar to Figure 1 showing a modified form of the invention.

Figure 7 is a vertical section taken on line 1—1 of Figure 6.

Figure 8 is a horizontal section taken on line 5—8 of Figure 6.

In the drawings the locks embodying the instant invention are illustrated in connection with the double doors of an automobile car. In this application of the locks they are shown fastened to the auxiliary door of the double door construction. The locks are to be understood to be applicable to freight cars utilizing a single door in each wall in which case the locks will be fastened to the car side wall. In this event, only such changes in the mode of attachment of the lock which are clear to those skilled in the art will be required. The structure of the locks, however, their function and association with the sliding doors with which they are related are un- affected.

The numeral 10 designates the auxiliary door of a double door construction utilized in cars wherein bulky lading such as automobiles, furniture and the like are shipped. The main door of this double door construction is designated by the reference numeral 11.

Insofar as pertinent to the instant invention the auxiliary door 10 embodies a metallic panel 12 provided with a plurality of spaced horizontal corrugations 13 which merge into the plane of the panel inwardly of the vertical edges thereof as indicated at 14. Secured to the inner face of the auxiliary door 10 at its forward margin is a post 15 substantially Z-shaped in section. The post 15 is riveted to this edge of the door as by rivets 16 so as to be movable with the door. The rivets 16 are utilized additionally to fasten to said edge of the door a substantially Z-shaped member 17 which provides a stop and in conjunction with the deformed flange 18 of the post 15 provides a recess 19 for the reception of the forward margin of the main door 11.

The main door 11 like the auxiliary door 10 embodies a metallic panel 12 having the spaced horizontal corrugations 13 formed therein which terminate short of the vertical edges of the doors as indicated at 14. The forward margin of the main door 11 is reinforced by means of a vertical stiffener 20 secured to said edge of the door as by rivets 21. The stiffening member 20 is provided with spaced vertical flanges 22 and 23, the former of which is adapted to engage the stop member 17 to limit closing movement of the main door and seal the meeting edges of the doors. The

flange 23 cooperates with the flange 24 of the door stop 17 which lies in overlapping relationship with the front margin of the main door to further aid in sealing the meeting edges of the 5 main and auxiliary doors.

In the double door construction illustrated, the novel lock is applied in its entirety to the auxiliary door 10 thus obviating the need for attachment of any of the lock parts to the main door 11. The lock embodies a base plate 25 secured to the auxiliary door as by rivets 26. The base plate embodies spaced front and rear walls 27 and 28 connected by the vertical wall 29 which as more clearly appears from Figure 3 of the 15 drawings abuts the main door stop 17. At its upper and lower ends the rear wall 28 merges into the plate attaching flanges 30 and 31 through which the rivets 26 extend. Hinge ears 32 and 33 project outwardly from the attaching flanges 10 20 30 and 31, these ears being connected with the upper and lower portions of the front wall 27 by means of the upper and lower portions 33 and 34 into which the said front wall merges. Openings 35 and 36 are formed in the hinge ears 32 25 and 33 and a hinge pin 31 is adapted to extend through these openings. The walls 27, 28 and 29 of the base plate 25 provide a housing for the reception of a vertically movable tapered pin 38. The base plate 25 is formed additionally with an 30 outwardly projecting staple 39 having an opening 40 extending therethrough.

The base plate 25 carries a locking member designated in its entirety by the reference numeral 41. In the embodiment of the invention illustrated in Figures 1 to 5 inclusive of the drawings, the locking member 41 comprises a rolled channel shaped member 42 having a web 43 and vertically disposed inwardly extending flanges 44 and 45. An angle member 46 preferably in the form of a 35 casting having flanges 47 and 48 is secured to the channel shaped member 42 as by means of rivets 49 extending through the web 43 of the channel member and the flange 47 of the cast angle member. The flanges 44 and 48 of the channel member and cast angle member, respectively, are secured together as by means of rivets 50. The angle member 46 is formed with integral 40 hinge ears 51 and 52 provided with elongated openings 53 and 54. The angle member 46 is shaped to provide an upwardly opening channel 45 recess defined by the spaced vertical flanges 55 and 56 and the horizontal connecting flange 57. Aligned seal receiving openings 58 and 59 are formed in the vertical flanges 55 and 56.

The cast angle member 46 carries the outwardly projecting vertically spaced flanges 60 and 61. These flanges are formed with openings and in conjunction with the vertical flanges 55 and 56 and the connecting horizontal flange 57 provide means for the reception of a locking pin 62 carried by the locking member.

When assembled the tapered pin 38 is disposed between the front and rear walls of the base plate and the locking member is connected to the base 65 plate by means of the hinge pin 31 which extends through the aligned openings formed in the ears provided respectively on the base plate and on the locking member.

The operation of the lock will be apparent from 70 the foregoing detailed description.

Assuming that the front edge of the main door 11 has been brought sufficiently close to the door stop 17 so as to permit the engagement of the said door by the locking member, the vertical flange 45 75 of the locking member will be brought into en-

gagement with the bearing plate 63 secured to the flange 22 on the vertical stiffener, preferably by means of welding. Inasmuch as the plate 63 and the flange 22 lie behind the overlapping flange 24 of the door stop 17, this flange is provided 5 with a recess 64 through which the flange 45 of the locking member extends for engagement with the bearing plate 63. The flange 44 of the locking member is engaged with one side of the tapered pin 38, the other side of which bears 10 against the flange 29 of the base plate. In this position of the locking member the staple 39 carried by the base plate extends through an opening 65 formed in the locking member and lies between the spaced flanges 60 and 61 provided 15 on the cast angle member 46. The locking pin 62 extends through an opening formed in the flange 57 and through the openings provided in the flanges 60 and 61 and in the staple 39. A seal may then be passed through the openings 58 and 20 59 formed in the vertical flanges 55 and 56 and through an aligned opening 66 formed in the pin 62 thus sealing the lock. Attention is invited to the fact that the opening 65 formed in the locking member is substantially longer than the 25 staple 39 formed on the base plate.

In the drawings the main door 11 is illustrated in engagement with the front stop 17 whereby the main door is fully closed. In view of the construction of the lock, however, it will be readily 30 apparent that secure locking of the main and auxiliary doors may be had when the main door is not fully closed. This is accomplished by reason of the elongated openings 53 and 54 35 formed in the ears 51 and 52 carried by the angle 30 member 46 of the locking member 41 and by the opening 65 formed in the locking member through which the staple 39 projects. With reference to Figure 3 of the drawings, it will be apparent that the locking member may be moved laterally until the clearance between the hinge 40 pin 37 and the elongated openings 53 and 54 is taken up and yet secure locking engagement between the locking member and the main door. The clearance between the staple 39 and the opening 65 formed in the locking member also permits this lateral movement of the locking member with respect to the doors. The main door can, therefore, be locked prior to assuming its full closed position. In this position of the main door the 50 tapered pin 38 abuts against the flange 29 of the base plate and the vertical flange 44 of the channel locking member. Movement of the main door in opening direction is thereby prevented. The main door, however, may move in closing direction whereupon the tapered pin 38 by the action of gravity will be lowered thereby moving the locking member toward the left as viewed in Figure 3 of the drawings and causing the slack 55 created by the closing movement of the door to be taken up. When the main door assumes its fully closed position illustrated in Figure 3 of the drawings, all movement either in closing or in opening direction is prevented.

In order to unlock the main door 11 the seal 65 which has been passed through the aligned openings 58, 59 and 66 is removed and the locking pin 62 is raised until it is disengaged from the staple 39. The tapered pin 38 is raised so as to be disengaged from the vertical flange 44 of the 70 locking member. The tapered pin 38 is limited in its elevation by means of a stop member 67 secured to the auxiliary door by means of a rivet 68. After the pins 38 and 62 are thus raised the locking member 41 is swung outwardly so as to be 75

disengaged from the plate 63 and the flange 24 of the front stop 17. Outward swinging movement of the locking member is limited by the engagement between the angular portions 69 of the hinge ears 51 and 52 with the auxiliary door 10, thereby insuring that the locking member will not project outwardly beyond the tunnel clearance line.

It will be clear from the foregoing description 10 that the lock is a self-contained unit capable of being pre-assembled and furnished as a unit to the railroads. It obviates the application of any lock parts to the main door of an automobile car or to the single door of a box car. It provides, by 15 reason of the continuity of the vertical flanges 44 and 45 of the channel locking member, bearing surfaces far in excess of bearing surfaces heretofore attainable in locks for sliding car doors. Moreover, the seal does not engage the tapered 20 pin so that danger of broken seals as a result of possible jumping of the pin is eliminated.

A modified form of the invention is illustrated in Figures 6, 7 and 8 of the drawings. The base plate 70 of the modified form of the invention 25 embodies front and rear walls 71 and 72 spaced transversely relative to the doors and connected by a vertical web 73. The side wall 74 of the base plate abuts the front stop 17 and is connected with the web 73 by means of the spaced ribs 30 75 and 76. At its upper end the rear wall 72 merges into the attaching flange 77 while at its lower end the rear wall 72 merges into an attaching flange 78. Rivets 79 passing through the attaching flanges 77 and 78 are used to fasten the 35 base plate to the auxiliary door 10.

The front wall 71 merges at its upper and lower ends, respectively into flanges 80 and 81 which are extended laterally in order to provide hinge ears 82 and 83. There is thus provided a housing 40 for the reception of a tapered pin 84 substantially the same as the tapered pin 38 with the exception that one side of the pin is formed so as to lie at an obtuse angle relative to the front face of the pin as indicated at 85.

In the considered embodiment of the invention 45 the locking member 86 is a cast member. This member is formed adjacent its upper and lower ends with reinforcing ribs 87 and 88 which as more clearly appears from Figure 6 of the drawings are extended laterally to provide hinge ears 89 and 90. The ears 89 and 90 are extended as indicated at 91 and 92 and the rear edges of these extensions are disposed at an angle to the auxiliary door as indicated at 93. In addition the hinge ears 89 and 90 are provided with elongated 50 openings 94 and 95.

The locking member 86 is further reinforced by means of the spaced ribs 96 and 97 between which an opening 98 is formed in the web 99 of the locking member. Through this opening a staple 100 formed integral with the base plate 70 is adapted to extend. Flanges 101 and 102 extend inwardly from the web 99 of the locking member, the flange 101 being adapted for engagement with the bearing plate 63 secured to the flange 22 of the door stiffener 20 and the flange 102 being adapted for engagement with the inclined side of the tapered pin 84. It will be observed that the flange 102 is therefore correspondingly inclined with regard to the inclined side of the tapered pin. The reinforcing ribs 60 96 and 97 are provided with vertically aligned openings as clearly indicated in Figure 6 of the drawings, whereby the locking member 86 is adapted to carry a locking and sealing pin 103.

Spaced vertical flanges 104 and 105 extend upwardly from the reinforcing rib 87. These flanges together with the upper end of the locking pin 103 are provided with horizontally aligned openings 106, 107 and 108 for the reception of a 5 seal.

A hinge pin 109 passing through the aligned openings in the ears provided on the base plate and on the locking member is utilized to swingably secure the locking member upon the base 10 plate.

With particular reference to Figure 7 of the drawings, it will be observed that the rivet 79 which lies in the path of movement of the tapered pin 84 has its head adjacent to the pin flattened 15 somewhat as indicated at 110. Also the rear face of the tapered pin is recessed as indicated at 111 so as to provide a groove within which the flattened head 110 of the rivet 79 is received. The groove 111 terminates in a shoulder 112 20 whereby the rivet head 110 is utilized in conjunction with the groove 111 and the shoulder 112 to limit the vertical lifting movement of the tapered pin.

It will be apparent without further description 25 that the lock of the considered embodiment of the invention possesses all of the attributes of the first described embodiment of the invention. It has the ability to absorb automatically any slack which might be introduced when the main 30 door is not fully closed. It provides at least the same desirable bearing area secured from the lock shown in Figures 1 to 5 inclusive of the drawings. In addition, by reason of the inclination of the side of the tapered pin and the conforming flange 35 102 which abuts said side, the locking member 86 may be swung to inoperative position without the necessity of first raising the tapered pin. This will become apparent from a consideration of Figure 8 of the drawings. The swinging movement of the locking member to its inoperative 40 position is limited by the rear edge 93 of the ears formed on the locking member so that said member will not project beyond the tunnel clearance line.

It will be apparent that numerous changes and 45 modifications in the details of the invention will be clear to those skilled in the art. It is intended, therefore, that all such modifications and changes be comprehended within this invention, 50 which is to be limited only by the scope of the claims appended hereto.

I claim:

1. A lock for sliding car doors comprising a base plate, a tapered pin carried by said base 55 plate, a staple on said plate, a channel shaped locking member, means mounting said lock member upon said base plate for swinging movement in a horizontal plane and for translatory movement, said locking member having a web and inwardly extending vertical flanges, one of said flanges engaging a side of said tapered pin in the operative position of said locking member and a locking pin carried by said locking member adapted to engage said staple to releasably fasten 60 said locking member to said base plate.

2. A lock for sliding car doors comprising a base plate, a tapered pin carried by said base plate, a staple and hinge ears projecting from said plate, a channel shaped locking member 70 having hinge ears provided with laterally elongated openings, a hinge pin extending through said ears on said base plate and said elongated openings in said hinge ears of said locking member, said locking member engaging said tapered 75 pin.

- pin when in operative position and a locking pin cooperable with said staple carried by said locking member.
3. A lock for sliding car doors comprising a base plate, a tapered pin carried by said base plate, a staple and hinge ears projecting from said plate, a channel shaped locking member having hinge ears provided with laterally elongated openings, a hinge pin extending through said ears on said base plate and said elongated openings in said hinge ears of said locking member, said locking member engaging said tapered pin when in operative position and a locking pin cooperable with said staple carried by said locking member, the rear edges of said hinge ears on said locking member having portions which are angularly related to limit swinging movement of said locking member in one direction.
4. A lock for sliding car doors comprising a base plate, a tapered pin carried by said base plate, a staple projecting from said plate, a locking member, means mounting said lock member for swinging and translatory movements relative to said plate, said locking member having spaced vertical flanges extending toward said tapered pin and door, said flanges being adapted to engage said tapered pin and a vertical member on said door, and means cooperable with said staple for releasably fastening said locking member to said base plate.
5. A lock for sliding car doors comprising a base plate, a tapered pin carried by said base plate, a staple and hinge ears projecting from said plate, a locking member having hinge ears, a hinge pin extending through aligned openings in said ears, the openings in the ears on said locking member being larger than said hinge pin, spaced vertical flanges on said locking member adapted to engage said tapered pin and a vertical member on said door, and means cooperable with said staple for releasably fastening said member to said base plate.
6. A lock for sliding car doors comprising a base plate, a tapered pin having a side inclined at an obtuse angle to the front face of said pin carried by said base plate, a staple projecting from said plate, a locking member, means mounting said lock member for swinging and translatory movements relative to said plate, said locking member having spaced vertical flanges extending toward said tapered pin and door, said flanges being adapted to engage said side of said tapered pin and a vertical member on said door, said flange engaging said side of said pin being similarly inclined, and means cooperable with said staple for releasably fastening said locking member to said base plate.
7. A lock for sliding car doors comprising a base plate, a tapered pin carried by said base plate, a staple projecting from said plate, a locking member, means mounting said lock member for swinging and translatory movements relative to said plate, said locking member having spaced vertical flanges extending toward said tapered pin and door, said flanges being adapted to engage said tapered pin and a vertical member on said door, means for limiting swinging movement of said locking member, and means cooperable with said staple for releasably fastening said locking member to said base plate.
8. A lock for sliding car doors comprising a base plate, a tapered pin carried by said base plate, a locking member, means mounting said lock member for swinging and translatory movements relative to said plate, said locking mem-
- ber having spaced vertical flanges extending in the same direction and toward said tapered pin and a member on said door, said vertical flanges being engageable with said tapered pin and said member and means for releasably fastening said locking member against swinging movement.
9. A lock for sliding car doors comprising a base plate, a tapered pin carried by said base plate, hinge ears projecting from said plate, a locking member having hinge ears, a hinge pin extending through aligned openings in said ears, the openings in the ears on said locking member being larger than said hinge pin, spaced vertical flanges on said locking member adapted to engage said tapered pin and a vertical member on said door, and means for releasably fastening said locking member against swinging movement.
10. A lock for sliding car doors comprising a base plate, a tapered pin carried by said base plate, a staple projecting from said plate, a locking member, means mounting said lock member for horizontal swinging and translatory movements relative to said plate, said locking member having spaced vertical flanges extending toward said tapered pin and door, said flanges being adapted to engage said tapered pin and a vertical member on said door, and means cooperable with said staple for releasably fastening said locking member to said base plate.
11. A lock for sliding car doors comprising a base plate, a tapered pin carried by said base plate, a staple on said plate, a channel shaped locking member, means mounting said lock member upon said base plate for swinging movement in a horizontal plane and for translatory movement, said locking member having a web and inwardly extending vertical flanges, one of said flanges engaging a side of said tapered pin in the operative position of said locking member, an aperture in said web through which said staple is adapted to project and a locking pin carried by said locking member for association with said staple to fasten said locking member to said base plate.
12. A lock for sliding car doors comprising a base plate, a staple projecting from said plate, gravity actuated take-up means carried by said plate, a locking member, means mounting said lock member for translatory and swinging movements relative to said plate, said locking member having spaced inwardly directed vertical flanges engageable with a vertical member on said door and said gravity actuated take-up means, and a locking pin carried by said locking member adapted to be associated with said staple for releasably fastening said locking member to said base plate.
13. A lock for sliding car doors comprising a base plate, a staple and hinge ears projecting from said plate, gravity actuated take-up means carried by said plate, a locking member having hinge ears, a hinge pin extending through aligned openings in said ears, the openings in the ears of said locking member being larger than said hinge pin, spaced inwardly directed vertical flanges on said locking member engageable with a vertical member on said door and said gravity actuated take-up means for absorbing slack of said door, and means carried by said locking member engageable with said staple for releasably fastening said locking member to said base plate.
14. A lock for sliding car doors comprising a base plate, gravity actuated take-up means car-

- ried by said plate, a locking member, means 5
mounting said lock member for swinging and
translatory movements relative to said base plate,
said locking member having spaced vertical
flanges extending in the same direction and en-
gageable with said gravity actuated take-up
means and a vertical member on said door, and
means for releasably fastening said locking mem-
ber against swinging movement.
- 10 15. In a railway house car having a sliding
door embodying a member, and a relatively sta-
tionary member carrying a door stop provided
with a flange overlapping said door, a base plate
secured to said relatively stationary member, a
15 staple on said plate, a locking member, means
mounting said lock member on said plate for
horizontal swinging and translatory movements,
a tapered pin carried by said plate, spaced verti-
cal flanges on said locking member, said flanges
20 engaging said tapered pin and said member on
said door, said door stop flange being coped to
permit said engagement with said member on

said door, and a locking pin carried by said lock-
ing member engageable with said staple to re-
leasably fasten said locking member to said base
plate.

16. In a railway house car having a sliding 5
door embodying a vertical member, and a rela-
tively stationary member carrying a door stop
having a slotted flange overlapping said door,
a base plate secured to said relatively stationary
member, take-up means carried by said base plate, 10
a locking member, means mounting said lock
member on said base plate for swinging and
translatory movements, spaced vertical flanges
on said locking member engaging said take-up
means and said vertical member on said door, 15
said vertical flange which engages said vertical
member on said door extending through said
slot for the purpose of said engagement, and
means releasably fastening said locking mem-
ber against swinging movement. 20

FRANK DITCHFIELD.
